SHIPPING CONTAINER REFRIGERATED
BY DRY ICE

Andrew J. Nicholas, North Haven, Conn., assignor to The Greaby Manufacturing Company, Plainville, Conn., a corporation of Connecticut

Application May 23, 1946, Serial No. 671,864

11 Claims. (Cl. 62—91.5)

1 The present invention relates to refrigeration and more particularly to a refrigerating unit utilizing solidified carbon dioxide or its equivalent as a primary refrigerant, which unit is admirably adapted to use in a portable refrigerator in the nature of a refrigerated shipping container.

There is definite utility for a shipping container of moderate size which may be handled very much as any ordinary container of equivalent size but which container comprises a portable refrigerator. In particular, such a refrigerated shipping container is of great value in providing for refrigerated shipment of relatively small quantities of perishable materials from scattered points by ordinary railroad car or truck and thus it is possible to furnish refrigerated shipping service to those communities whose location or size does not warrant the use of refrigerated railroad cars or refrigerated truck or trailer units.

It is an object of the present invention to provide a refrigerating unit which may be conveniently handled and recharged and which automatically functions at a modulated temperature suitable for particular perishable products while using as the primary refrigerant solidified CO₂ or other similar material which has extremely low temperature. For example, the temperature of solidified CO₂ is -108° F. and such temperature is of course incompatible with such perishable commodities as fresh vegetables and the like.

It is a further object of the present invention to provide a refrigerating unit utilizing solidified CO₂ as a primary refrigerant and which will operate to maintain a desired moderately cool temperature without moving parts or mechanical regulating devices.

It is a further object of the present invention to provide a refrigerating unit of the type described which will operate for periods of time sufficient to permit relatively long distance shipment of a refrigerated commodity without the necessity for recharging or servicing of the refrigerating unit.

It is a further object of the present invention to provide a refrigerating unit which utilizes solidified CO₂ as a primary refrigerant and which utilizes a liquid secondary refrigerant having a predetermined freezing point and to provide for heat exchange between evaporated gaseous CO₂ and the secondary refrigerant.

It is a further object of the present invention to provide a refrigerating unit as set forth in the next preceding object in which the gaseous CO₂ is conducted after heat-exchange with the secondary refrigerant to such a point in the refrigerating

2 erated space as to cause positive circulation of the atmosphere in such space.

It is a further object of the present invention to provide a portable refrigerator having a load-carrying compartment into which a commodity needing refrigeration may be placed and a readily removable refrigerating unit which may be inserted into the refrigerator and removed therefrom for servicing, recharging or replacement without disturbing the commodity.

It is a further object of the present invention to provide a refrigerated shipping container adapted to receive a load of material needing refrigeration and which is provided with a readily removable refrigerating unit utilizing solidified CO₂ as a primary refrigerant and which may be replaced or recharged along the line of shipment.

Other and further objects of the present invention will become apparent from a consideration of the following detailed description of a preferred form of the invention taken in connection with the drawings accompanying and forming a part of this specification.

25 In the drawing the figure is a sectional view of a refrigerator made in accordance with the present invention.

Referring now to the drawing, there is shown a refrigerator comprising a cabinet 10 having 30 a food storage or load-carrying compartment 12 and one or more movable closures 14 providing access to the compartment 12. The refrigerator also comprises a refrigerating unit indicated generally at 16 which is insertable into the body of 35 the cabinet through an opening of suitable size which is closed by a movable closure 18. It is to be understood that the cabinet 10 may have any suitable shape. The form illustrated is generally rectangular in shape, having end walls 20, front 40 and back walls 22, only one of which is shown in the drawing, a bottom wall 24 and a top wall 26. Each of the walls 20, 22, 24, and 26 as well as movable closures 14 and 18 may be hollow and provided with suitable heat-insulating material 28 as is common in the manufacture of refrigerator cabinets. Desirably, the walls aforesaid and the movable closures are formed of some relatively light and durable metal to permit ease of handling of the cabinet.

50 The movable closures 14 and 18 may be hinged or bodily removable as preferred, and it will be understood that the openings for which these closures are provided may be equipped with gaskets 30 made of rubber or other suitable material.

The opening 32 which is closed by the closure 18 is preferably square in shape. This opening is defined by four vertical walls 34 extending into the body of the cabinet 16 and terminating in horizontally disposed flanges 36. The opening thus lying between the flanges 36 is of such size as readily to admit the refrigerating unit 16.

A foraminous enclosure is provided for the refrigerating unit 16 and in the embodiment chosen for illustration, such enclosures may comprise suitable panels of screen wire 38 secured at their upper edges to the flanges 36 and along their vertical edges to the front and rear walls 22 as by brackets 40. This foraminous enclosure thus is preferably a permanent part of the refrigerator cabinet and serves to prevent direct contact between the perishable commodity stored therein and the refrigerating unit 16. Furthermore, the provision of such an enclosure assures that the refrigerating unit 16 may be removed and replaced without disturbing the load within the cabinet. It will be understood that the foraminous enclosure need only be slightly larger than the refrigerating unit 16, and that in the event the cabinet 16 is so proportioned as to be considerably wider in a direction perpendicular to the plane of the sectional view of the drawing than is the unit 16, the foraminous enclosure may take the form of a basket closed on all four sides by screen or other suitable material similar to the panels 38.

The refrigerating unit 16 comprises upper and lower rigidly connected containers 42 and 44, respectively, which will be described in greater detail herein below. The upper container 42 is provided with elongated angles 46 secured adjacent all four upper edges thereof, the horizontally extending flanges 48 of which rest upon the flanges 36 within the opening 32. The refrigerating unit 16 is thus supported on all four sides merely by resting upon the flanges 36 and the unit may thus be readily lifted from the refrigerator when the closure 18 is opened.

The refrigerating unit 16 will now be described in detail. The upper container 42 is adapted to receive a block 50 of solidified CO₂. Preferably, the container 42 is provided with an inner basket 52 made of screen or other suitable foraminous material which serves to keep the solidified CO₂ out of direct contact with the walls of the container 42.

The container 42 is preferably made of metal and is adapted to be closed in a substantially gas-tight manner. To this end, there may be provided a gasket 54 made of rubber or other suitable material extending around the upper open end of the container 42. A closure 56 is provided to rest upon the gasket 54 and may be drawn tightly into place by a suitable number of screws 58 provided around the margins of the closure 56. The screws 58 may be threadably received in fixed nuts 60 provided within the angles 46. Preferably, the gasket 54 is relatively thick and soft in order to provide not only for sealing of the container 42 under normal conditions, but also to permit escape of gas therearound in the event a dangerous pressure is developed within the container 42. A handle 62 may be secured to the closure 56 to facilitate lifting of the unit 16 and removal of the closure 56 from the unit when desired.

The lower container 44 is preferably supported by the upper container 42 and is spaced therefrom in order to provide substantially no direct heat transfer between the two containers 42 and

44. To this end a plurality of angle brackets 64 are secured as by welding to the lower exterior surface of the upper container 42. The brackets 64 are spaced from one another as far as practicable, having due regard to strength requirements. The horizontally disposed arms of the brackets 64 extend outwardly beyond the exterior surfaces of the vertical walls of the upper container 42 and thus the vertically disposed arms of the brackets 64 are spaced outwardly from such vertical surfaces. An intermediate container 66 is secured to the outer vertical surfaces of the brackets 64 and this intermediate container comprises four vertical walls 68 which extend horizontally beyond the upper container 42 and a relatively narrow shelf-like bottom 70 extending around all four sides thereof. The bottom 70 is formed with downwardly turned flanges 72 which are in turn secured to the exterior surfaces of the lower container 44 and thus serve to support the same.

The intermediate container 66 is open at its top all the way around the upper container 42, such opening existing between the angle brackets 64 and within the space between the walls 68 of the intermediate container and the vertical walls of the upper container 42. The intermediate container 66 is thus positioned to catch water from melting frost on the surfaces of the upper container 42 and to hold such accumulated moisture until such time as it may be removed by operation of a suitable pet cock 74.

The lower container 44 is provided for a liquid secondary refrigerant and is therefore liquid-tight. It is also gas-tight except for the passages provided therein for the introduction and removal of gas in the operation of the device. A liquid secondary refrigerant 76 is positioned within the lower container 44 and the quantity thereof is such as to leave a substantial head space thereabove within the container 44.

Particularly where the refrigerating unit is to be used in portable equipment it is desirable to provide a suitable number of baffle plates 78, 80 and 82 to reduce surging of the liquid. It has been found desirable to keep the level of the liquid below that of the lower surface of the uppermost baffle plate 82. The baffle plates 78, 80 and 82 are so positioned as to permit free circulation of the liquid within the container 44 and to permit free passage of gas through such liquid in operation of the device. As shown in the drawing, the upper baffle plate 82 is preferably so positioned as to permit flow of gas around the edges thereof with as little restriction as possible and thus this baffle plate may be supported by suitable angle brackets 64 secured to side walls of the container 44.

The exterior surfaces of the lower container 44 are preferably provided with fins 86 to increase the area of the surfaces of the container. The fins 86 may be formed from metallic angles welded or otherwise secured to the surfaces of the container 44.

Heat exchange between the solidified CO₂ in the upper container 42 and the secondary refrigerant in the lower container 44 is, except for minor conduction through the brackets 64 and walls 68 of the intermediate container 66, solely effected by the passage of gaseous CO₂ formed upon evaporation of the solidified CO₂. To this end one or more tubes or conduits 88 are provided, the upper ends 90 of which open into the upper container 42. The conduits 88 are extended downwardly through the walls 68 and through

the top 92 of the lower container 44. The conduits 88 then extend downwardly within the container 44 to a point very close to the bottom thereof. The conduits 88 may be open at their lower ends or not, as may be preferred. In either event it is important that a plurality of vertically spaced openings 94 be formed therein extending for a substantial distance upwardly of the conduit 88. All of the openings 94 should be located below the level of the top of the secondary refrigerant 76.

The top wall 92 of the lower container 44 also has formed therein one or more openings 96 providing for the escape of gas leaving the surface of the secondary refrigerant. It is preferred to provide conduits 98 in each of such openings 96 which conduits extend upwardly to a point adjacent the top of the refrigerating unit 16 and in proximity to the surfaces of the upper container 42. Ordinarily a conduit 98 will be provided for at least two of the external vertical surfaces of the upper container 42 and if desired, such a conduit may be provided for all four vertical walls. The conduits 98 are open at their upper ends to permit escape of gas in a region which not only is in proximity to the upper exterior surfaces of the upper container 42, but also is the upper region of the load-carrying compartment itself.

In order that the operation of the refrigeration unit may be understood, it will be described first in general terms and then in a specific embodiment. A secondary refrigerant 76 is chosen having a freezing point such as to meet the requirements at hand. For example, water may be chosen. The secondary refrigerant is placed in the lower container 44 and the quantity thereof is so chosen as to fill the container 44 to approximately 75%-80% of its capacity. A quantity of solidified CO₂ is placed in the upper container 42 and the closure 56 is secured. The unit 16 is then positioned within the cabinet 10 and the closure 18 is closed.

Assuming that there is no food load in the compartment 12 and assuming that the air in said compartment is at a normal room temperature of 70° F., it will be apparent that the solidified CO₂

50 will begin to sublime or evaporate and that the gaseous CO₂ will soon begin to flow through the conduit 88. When sufficient pressure has developed, the gaseous CO₂ will begin to bubble upwardly through the secondary refrigerant water 76. Some of the CO₂ will be dissolved in the secondary refrigerant and the remainder will bubble completely through it and escape into the head space above the baffle 82 from which it will be discharged through the conduit or conduits 98. As the gaseous CO₂ passes through the water 76, heat exchange occurs and the CO₂ is relatively warm as it leaves the upper end of the conduit 98. It is still colder and heavier than the atmosphere of the compartment 12 and furthermore is discharged in a region adjacent the relatively cold exterior surfaces of the upper container 42. Thus the gaseous CO₂ will descend along the exterior surfaces of the upper container 42, the intermediate container 66 and the finned lower container 44. This produces a positive scrubbing of such exterior surfaces and produces a positive circulation of the atmosphere in the compartment 12.

Such operation proceeds until the atmosphere has been considerably cooled and the temperature of the secondary refrigerant has been brought down substantially to the freezing point thereof.

In the meantime a portion of the moisture in the atmosphere of compartment 12 will have been deposited on the exterior surfaces of the upper container 42 in the form of a layer of frost. Such frost layer will build up quickly in view of the largely indirect heat transfer between the walls of container 42 and the extremely cold solidified CO₂ therein. The frost layer serves to insulate the upper container 42, sharply reducing the rate of sublimation of the CO₂ therein and also exposing the gaseous CO₂ emerging from conduit 98 to a much higher temperature than that encountered at first. The atmosphere of the compartment 12 is much cooler than at first thus further reducing the rate of sublimation of the solidified CO₂.

It will be recognized that the conditions just described have a strong tendency toward equilibrium and if it were not for heat inflow through the cabinet 10 the secondary refrigerant would eventually freeze solid. The equilibrium is not too precarious, however, because of such heat inflow and because of the tremendous amount of energy required to remove the latent heat of fusion of a liquid and bring about freezing thereof when it is substantially at its freezing point. As a consequence the secondary refrigerant 76 serves as "heat flywheel." The temperature of the secondary refrigerant will hover substantially at the freezing point thereof, irrespective of relatively great changes in the other conditions established in the refrigerator.

Inasmuch as the equilibrium established is dependent upon the freezing point of the secondary refrigerant, it is possible to vary the temperature at which the atmosphere of the compartment 12 is maintained by selection of secondary refrigerants having different freezing points. When water is used and no food load is carried in the compartment, it has been found that the atmosphere will be maintained at a temperature of about 34° to 36° F., assuming of course that the unit 16 is properly proportioned to the compartment 10. The equilibrium established in a well insulated empty compartment is rather delicate but this is not a condition which would be encountered in normal use of the device. A food load produces heat, different foods having different characteristics, as is well known. For example, string beans produce a relatively great amount of heat and have been considered to be difficult to ship under refrigeration. In the normal use of the present invention, the heat produced by the food load plus the heat inflow in the cabinet will keep a unit 16 of proper size working at a relatively slow rate with no danger of freezing up. It has been found that excellent results are achieved when the compartment temperature is established at about 10° or 12° F. higher than the freezing point of the secondary refrigerant.

When the unit 16 is in operation at its best efficiency, the secondary refrigerant will usually freeze and thaw to a certain extent, at most to a point where some slush will float to the top. As pointed out above the apparatus must be designed to avoid solid freezing inasmuch as this would prevent bubbling of the gaseous CO₂ through the secondary refrigerant. However, this is not particularly difficult and the fact that the secondary refrigerant has a quantity of CO₂ dissolved in it will lead to formation of a porous slush rather than solid ice. The specific embodiment to be described below is illustrative of a relationship between size of compartment 12 and quantities

of primary and secondary refrigerants which result in operation free of danger of freeze-ups.

Because of the formation of slush discussed above, the provision of a vertically spaced plurality of openings 94 in the conduit 88 is of particular advantage. If one or more of the upper openings should be plugged by slush, the lower openings will remain open. The plurality of openings is preferable to a single opening, say merely the open end of the conduit itself, because of the tendency toward formation of ice at this point of first contact between the cold CO₂ gas and the liquid. When a plurality of openings is provided good circulation is assured and the building up of ice at the openings is avoided.

The circulation of the secondary refrigerant 16 within the lower container 44 results in rapid heat transfer and in effect the interior walls of the container 44 are scrubbed in much the same manner as the exterior walls.

A specific embodiment of the invention comprises an outer cabinet 10 made of aluminum alloy, insulated with spun glass and having an interior volume of twelve cubic feet. The foraminous enclosure 38 and refrigerating unit 16 therein occupy three cubic feet thus leaving nine cubic feet for storage of a commodity. Three and one-half gallons of water having one and three-fourths pound of CaCl₂ dissolved therein is placed in the lower container 44 as a secondary refrigerant. The container 44 is eighty percent full. If approximately fifty pounds of solidified CO₂ (about a ten-inch cube) is placed in the upper container and the compartment 12 is filled with string beans, for example, a temperature of from 35° F. to 37° F. will be maintained in the compartment 12 for a period of about four days. The freezing point of the CaCl₂ solution used as a secondary refrigerant is 25° and as pointed out above a food load will lead to maintenance of a compartment temperature about 10° to 12° F. higher than such freezing point.

Obviously it would be advantageous to pre-cool the food load to prolong the effectiveness of a given quantity of solidified CO₂. If the shipment requires more than the three or four day period for which the original charge is good the shipping container must be serviced.

Servicing of the shipping container may be carried out by removing the unit 16 therefrom and inserting an identical unit having a proper quantity of solidified CO₂ therein. Suitably located servicing depots may be established for this purpose. Alternatively, the shipping container may be serviced merely by adding solidified CO₂ to the upper container 42.

When a unit 16 is exhausted of its charge of solidified CO₂ and warms up the frost on the upper container 42 will melt, dripping into the intermediate container 66. Ordinarily this will not occur when the unit 16 is positioned within a shipping container filled with a commodity inasmuch as it is contemplated that the units will be removed or serviced before exhaustion. However, the construction just described will prevent water damage to the contents of the shipping container in the event defrosting should occur.

It is thus apparent that there has been disclosed a refrigerator and refrigerating unit therefor which accomplishes the objects of the invention. The description is presented in an illustrative rather than in a limiting sense, and it will be understood that modifications and variations in detail may be resorted to by those skilled

in the art within the scope of the following claims. For example, any solidified material which exists as a gas at ordinary atmospheric temperatures and pressures may be substituted for the solidified CO₂ if so desired.

I claim:

1. In a refrigerator having a load-carrying compartment for storage of articles in a refrigerated gaseous atmosphere, a substantially gas-tight container for solidified CO₂ located within said compartment, a container having a secondary refrigerant therein located within said compartment substantially out of direct heat-exchanging relationship with solidified CO₂ in said first-named container, means to conduct evaporated gaseous CO₂ from said first-named container into heat-exchanging relationship with said secondary refrigerant, and means for continuously discharging said gaseous CO₂ after heat-exchange with said secondary refrigerant into an upper region of said refrigerated compartment whereby to cause forced circulation of the atmosphere in said compartment.

2. In a refrigerator having a load-carrying compartment for storage of articles in a refrigerated gaseous atmosphere, a substantially gas-tight container for solidified CO₂ located within said compartment, a container having a secondary refrigerant therein located within said compartment substantially out of direct heat-exchanging relationship with solidified CO₂ in said first-named container, means to conduct evaporated gaseous CO₂ from said first-named container into heat-exchanging relationship with said secondary refrigerant, and means for thereafter conducting said gaseous CO₂ to a zone in proximity with the upper exterior surfaces of said first-named container.

3. In a refrigerator having a load-carrying compartment for storage of articles in a refrigerated gaseous atmosphere, a substantially gas-tight container for solidified CO₂ located within said compartment, a second container located substantially directly beneath said first-named container, said second container having a secondary refrigerant therein substantially out of direct heat-exchanging relationship with solidified CO₂ in said first-named container, means to conduct evaporated gaseous CO₂ from said first-named container into heat-exchanging relationship with said secondary refrigerant and means for thereafter conducting said gaseous CO₂ to a position for release into said compartment in a zone adjacent the upper exterior surfaces of said first-named container whereby said relatively cool, relatively heavy released gaseous CO₂ will descend along the exterior surfaces of said first-named container and then along the exterior surfaces of said second-named container.

4. In a refrigerator having a load-carrying compartment for storage of articles in a refrigerated gaseous atmosphere, a substantially gas-tight container for solidified CO₂, said container being located within and near the top of said compartment, a second container having a secondary refrigerant therein, said second container being spaced from said first container to substantially prevent direct heat-exchange between said secondary refrigerant and solidified CO₂ in said first container, means to conduct evaporated gaseous CO₂ from said first-named container into said second container in heat-exchanging relationship with said secondary refrigerant, and means for continuously discharging said gaseous

CO₂ after heat-exchange with said secondary refrigerant into said refrigerated compartment.

5. In a refrigerator having a load-carrying compartment for storage of articles in a refrigerated gaseous atmosphere, a substantially gas-tight container for solidified CO₂ located within said compartment, a second container, a secondary liquid refrigerant positioned within said second container, means for mounting said second container in predetermined spaced relationship with said first container substantially to prevent direct heat-exchange between said secondary refrigerant and solidified CO₂ in said first container, at least one conduit connecting said first container and said second container, said conduit having an opening located below the level of the top of said secondary refrigerant whereby evaporated gaseous CO₂ will be conducted from said first container to said second container and may bubble through said secondary refrigerant for heat-exchange therewith, and said second container having an opening formed therein above the level of said secondary refrigerant for the discharge from said second container of said gaseous CO₂ after it leaves said secondary refrigerant.

6. In a refrigerator having a load-carrying compartment for storage of articles in a refrigerated gaseous atmosphere, a substantially gas-tight container for solidified CO₂ located within said compartment, a second container, a secondary liquid refrigerant positioned within said second container, means for mounting said second container in predetermined spaced relationship with said first container substantially to prevent direct heat-exchange between said secondary refrigerant and solidified CO₂ in said first container, at least one conduit connecting said first container and said second container, said conduit terminating adjacent the bottom of said second container and being provided with a plurality of openings therein located within and below the level of the top of said secondary refrigerant whereby evaporated gaseous CO₂ will be conducted from said first container to said second container and may bubble through said secondary refrigerant for heat-exchange therewith, and said second container having an opening formed therein above the level of said secondary refrigerant for the discharge from said second container of said gaseous CO₂ after it leaves said secondary refrigerant.

7. In a refrigerator having a load-carrying compartment for storage of articles in a refrigerated gaseous atmosphere, a substantially gas-tight container for solidified CO₂ located within said compartment, a second container, a secondary liquid refrigerant positioned within said second container, means for mounting said second container in predetermined spaced relationship with said first container substantially to prevent direct heat-exchange between said secondary refrigerant and solidified CO₂ in said first container, at least one conduit connecting said first container and said second container, said conduit terminating adjacent the bottom of said second container and being provided with a plurality of vertically spaced openings therein located within and below the level of the top of said secondary refrigerant whereby evaporated gaseous CO₂ will be conducted from said first container to said second container and may bubble through said secondary refrigerant for heat-exchange therewith, and at least one conduit opening into said second container above the level of said secondary refrigerant and extending upwardly to a region in

proximity with the exterior surface of said first container for discharge of said gaseous CO₂ into said region.

8. In a portable refrigerator having a load-carrying compartment for storage of articles in a refrigerated gaseous atmosphere, a substantially gas-tight container for solidified CO₂ located within said compartment, a second container, a secondary liquid refrigerant positioned within said second container, the quantity of said secondary refrigerant being such as to leave substantial head space in said second container above the level of the top of said secondary refrigerant, a plurality of baffle plates positioned in said second container to minimize surging of said secondary refrigerant during movement of said refrigerator, means for mounting said second container in predetermined spaced relationship with said first container substantially to prevent direct heat-exchange between said secondary refrigerant and solidified CO₂ in said first container, at least one conduit connecting said first container and said second container, said conduit having at least one opening located within and below the level of the top of said secondary refrigerant whereby evaporated gaseous CO₂ will be conducted from said first container to said second container and may bubble through said secondary refrigerant for heat-exchange therewith, and said second container having an opening formed in the head space portion thereof for the discharge therefrom of said gaseous CO₂ after it leaves said secondary refrigerant.

9. In a refrigerator having a load-carrying compartment for storage of articles in a refrigerated, gaseous atmosphere, a substantially gas-tight container for solidified CO₂ located within said compartment, means for holding a supply of a secondary refrigerant within said compartment substantially out of direct heat-exchanging relationship with solidified CO₂ in said container, means to conduct evaporated gaseous CO₂ from said container into heat-exchanging relationship with said secondary refrigerant, and means for thereafter conducting said gaseous CO₂ to a zone in proximity with the upper exterior surfaces of said container.

10. In a refrigerator having a load-carrying compartment for storage of articles in a refrigerated, gaseous atmosphere, a substantially gas-tight container for solidified CO₂ located within said compartment, means for holding a supply of a liquid secondary refrigerant within said compartment in spaced relationship with said container substantially to prevent direct heat-exchange between said secondary refrigerant and solidified CO₂ in said container, at least one conduit extending from said container and having an opening located below the level of the top of said secondary refrigerant from which evaporated gaseous CO₂ may bubble through said secondary refrigerant for heat-exchange therewith, and means for discharging said gaseous CO₂ after it leaves said secondary refrigerant into an upper region of said refrigerated compartment whereby to cause forced circulation of the atmosphere in said compartment.

11. A refrigerated shipping container comprising a heat-insulated body having at least one closure movable for providing access to a load-carrying compartment therein; a foraminous enclosure secured within said compartment and defining a sub-compartment from which articles stored in said load-carrying compartment are excluded by said foraminous enclosure; at least

one closure movable for providing access to said sub-compartment; and a refrigerating unit positioned in said sub-compartment in spaced relation to said foraminous enclosure, said refrigerating unit arranged to utilize solidified CO₂ as a primary refrigerant and having a secondary liquid refrigerant through which gaseous CO₂ may bubble upon evaporation of said solidified CO₂, and said refrigerating unit including means for continuously discharging the gaseous CO₂ leaving said secondary refrigerant into the load-carrying compartment to cause forced circulation of the atmosphere within said compartment.
